US00D547630S

(12) **United States Design Patent** (10) **Patent No.:** **US D547,630 S**
Fisher et al. (45) **Date of Patent:** **** Jul. 31, 2007**

(54) **CHAIN SAW**

(75) Inventors: **David B. Fisher**, Bowling Green, KY (US); **David E. Champlin**, Bowling Green, KY (US); **Douglas Sims**, Bowling Green, KY (US)

(73) Assignee: **Desa IP, LLC**, Miami, FL (US)

(**) Term: **14 Years**

(21) Appl. No.: **29/237,719**

(22) Filed: **Sep. 6, 2005**

(51) **LOC (8) Cl.** **08-03**

(52) **U.S. Cl.** **D8/65**

(58) **Field of Classification Search** **D8/7, D8/8, 9, 68, 70, 65, 66, 67, 62, 63, 64, 61; 30/386, 383, 362, 371, 123; 125/21**

See application file for complete search history.

DE 3433746 3/1986

(Continued)

Primary Examiner—Cathron C. Brooks*Assistant Examiner*—Austin Murphy(74) *Attorney, Agent, or Firm*—Alexander P. Brackett; Middleton Reutlinger(57) **CLAIM**

The ornamental design for a chain saw, as shown and described.

DESCRIPTION

FIG. 1 is a perspective view of our chain saw design;

FIG. 2 is a left view thereof;

FIG. 3 is a right side view thereof;

FIG. 4 is a bottom side view thereof;

FIG. 5 is a front view thereof;

FIG. 6 is a back view thereof; and,

FIG. 7 is a top view thereof.

The broken lines shown in the drawings form no part of the claimed design.
